UNITED STATES PATENT OFFICE.

FRED G. MOWER, OF ANTRIM, NEW HAMPSHIRE, ASSIGNOR TO GOODELL COMPANY, OF ANTRIM, NEW HAMPSHIRE, A CORPORATION OF NEW HAMPSHIRE.

APPLE PARER AND CORER.

1,113,571.

Specification of Letters Patent.

Patented Oct. 13, 1914.

Application filed May 27, 1911. Serial No. 629,801.

To all whom it may concern:

Be it known that I, FRED G. MOWER, a citizen of the United States, residing at Antrim, county of Hillsboro, State of New Hampshire, have invented an Improvement in Apple Parers and Corers, of which the following description, in connection with the accompanying drawing, is a specification, like characters on the drawing representing like parts.

This invention relates to apple parers and corers, and has for its object to provide a simple and inexpensive device which is provided with a manually-manipulated coring spoon so that it may be used or not as desired, and to provide a novel construction of coring spoon which will permit the latter to enter the apple to cut the core therefrom without danger of breaking or splitting the apple, and to otherwise improve machines of this class, all as will be more fully hereinafter described and then pointed out in the appended claims.

Referring to the drawings wherein I have illustrated one embodiment of my invention, Figure 1 is a front view of the device; Fig. 2 is an end view looking toward the left Fig. 1; Fig. 3 is a rear view of the paring head; Fig. 4 is a detail view of the turn-table; Fig. 5 is a top plan view of the machine; Fig. 6 is a section on the line $x-x$, Fig. 1; Fig. 7 is a section on the line $y-y$, Fig. 1; Fig. 8 is an enlarged longitudinal section of the fork shaft; Fig. 9 is a section on the line $a-a$, Fig. 8.

The frame of my improved machine comprises the head portion 1 on which the fork and the paring knife are sustained and which is provided with a clamp 2 for engaging the edge of a table 3 and an extension having at its end a second clamp 5 that is also adapted to be clamped to the edge of the table 3. The extension is herein formed by a sheet metal member 4 which is secured at one end to the underside of the projection 6 formed on the head frame 1 and at the other end to the top of the clamp 5, said sheet metal member 4 preferably being provided with the vertical flange 7 in order to give stiffness thereto. The clamp 5 and head frame 1 are also connected by

guide rods 8 on which the coring spoon holder is slidably mounted, as will be presently described.

The head 1 has journaled therein the fork shaft 9 carrying at its end the usual fork 10 and also has journaled therein a turn-table 11 operating in a substantially horizontal plane and to the underside of which is pivotally connected the stem 12 carrying the paring knife 160. The fork shaft 9 and the turn-table 11 are driven from a driving gear 13 having a handle 14 thereon and being connected to a gear 15 on the fork shaft through an idler 22 and being mounted on a shaft 16 which carries at its inner end a gear 17 that meshes with gear teeth 18 formed on the top of the turn-table. This manner of driving the turn-table and the fork is one which is in more or less common use and does not constitute part of the present invention. The stem 12 of the knife projects up through the turn-table and its upper end is adapted to engage a cam surface 19 formed on an arm 20 extending from the frame 1, said arm being provided with the bearing 21 in which the turn-table 11 is journaled. The operation of the turn-table 11 and paring knife is familiar to those skilled in the art and no further description thereof is necessary.

Associated with the fork 10 is a core doffer 23 which is provided with a stem 24 which is slidably mounted through an aperture 26 formed in the head 27 of the fork 85 and occupies a slot or groove 25 formed in the shaft 9, the end of said stem being connected to a ring 28 which encircles the shaft 9. This core-doffer or push-off is operated by a lever 30 pivoted at 31 to the frame and having at its lower end a loop or eye 32 which embraces the shaft 9 behind the ring 28. The loop 32 is shown as a piece of wire bent to embrace the shaft and provided with the arm 33 which extends through an aperture 34 formed in the foot 35 of the lever 30, this construction affording a suitable swivel connection between the lever and the eye to permit the parts to work freely. The turn-table 11 is provided on its periphery 100 with a cam 36 which is adapted to engage the upper end of the lever 30 at the point in

the cycle of operations when the core is to be doffed, the engagement of said cam with the lever 30 serving to rock said lever about its pivot and below the lower end thereof 5 and the eye 32 toward the right Fig. 3, said eye acting on the ring 28 thereby to project the core doffer as will be obvious. A spring 37 serves to return the lever 30 to its initial position after the cam 36 has passed.

10 38 designates a coring spoon holder which is provided with a foot portion 39 that is slidably mounted on the guide rods 8, said foot portion extending underneath the sheet metal member 4, as clearly seen in Fig. 6. A 15 coring spoon 40 is sustained by the holder 38, said coring spoon being clamped to the holder in any suitable way, as by means of a clamp block 41. The holder 38 is freely movable on the guide rods 8 and is intended 20 to be manually moved to perform the coring operation. To permit this to be done said holder is provided with the extension 42 which can be readily gripped between the thumb and finger of the operator's left hand 25 and by which the holder can be readily moved toward and from the coring fork in performing the coring operation.

I have provided a novel construction of coring spoon which will core the apple without any danger of cracking or breaking it. 30 Coring spoons are quite commonly made semi-cylindrical in shape throughout their entire length, but such a coring spoon is very likely to split the apple because of the engagement of the edges of the shank thereof with the apple as the coring spoon is advanced through the apple, this being especially true if the apple is not held perfectly true by the fork. In my improved coring 40 spoon I make the cutting edge 43 thereof substantially semi-cylindrical, but I form said coring spoon with a neck portion 440 of considerably reduced width so that when the coring spoon enters the apple the narrow 45 neck portion 440 will not engage the sides of the core hole formed in the apple with sufficient friction to cause the apple to crack or split. The reduced neck portion 440 is formed by cutting out one or both of the 50 edges of the coring spoon as at 45, and I preferably do this in such a way as to form one or more barbs or points 44 immediately back of the cutting edge. These barbs have the function of assisting to withdraw the 55 apple from the fork 10 when the coring spoon is retracted, for it will be readily seen that when the coring spoon begins its retracting movement after it has entered the apple, these barbs 44 will engage the walls 60 of the core hole and will by their engagement therewith assist in withdrawing the apple from the fork.

46 is a trimming knife which is provided with a shank 47 that is adjustably secured

to the frame 1 by means of clamping screws 65 48, said trimming knife being for the purpose of trimming around the stem of the apple.

In the operation of the device the apple is placed on the fork and the paring mechanism is operated in usual manner, and as soon as the cycle of operations has proceeded to the point where the paring is completed and the knife is thrown back out of engagement with the apple, the operator will advance the coring spoon holder 38 thereby to core the apple and will then retract said coring spoon holder thereby to withdraw the cored apple from the fork. At this time the core doffer 23 will be operated to doff the 80 core and the machine is in condition to receive another apple.

Having fully described my invention, what I claim as new and desire to secure by Letters Patent is:—

85 1. In an apple parer, the combination with a frame, of paring mechanism thereon, a reciprocating coring spoon holder, and a coring spoon sustained by the holder and provided with barbs at its side edges back 90 of the cutting edge but situated in line therewith.

2. In an apple parer, the combination with a frame, of paring mechanism thereon, a reciprocating coring spoon holder, and a coring spoon sustained by the holder and having a semi-circular shape and provided at one end with a cutting edge, each side of said coring spoon being cut out thereby to form a neck of reduced width and two 100 apple-withdrawing barbs.

3. In an apple parer, the combination with a frame, of a paring knife and means to operate it, a fork shaft having a fork thereon and a groove extending longitudinally thereof, a core doffer situated axially of the shaft and provided with a stem slidably mounted in the groove, the inner end of said stem being bent laterally through the groove and formed into a ring embracing 110 the shaft, a lever pivoted to the frame, an eye also embracing the shaft in the rear of the ring and connected to the lever, and means to operate the lever.

4. In an apple parer, the combination with a frame, of a paring knife and means to operate it, a fork shaft having a groove extending longitudinally thereof, a core doffer situated axially of the shaft and provided with a stem slidably mounted in said 120 groove, a ring embracing the shaft and connected to the end of the stem, a lever pivoted to the frame and provided with means to engage said ring, and means to operate the lever.

125 5. In an apple parer, the combination with a frame, of paring mechanism thereon, a reciprocating coring spoon holder, and a

coring spoon sustained by the holder and having a semi-circular shape and provided at one end with a cutting edge, said coring spoon being cut out at one side to form a neck of reduced width and an apple-withdrawing barb.

In testimony whereof, I have signed my

name to this specification, in the presence of two subscribing witnesses.

FRED G. MOWER.
